Patented May 15, 1917.

2 SHEETS—SHEET 2.

A technical drawing of a mechanical assembly, likely a component of a larger machine. The drawing shows a central rectangular frame with various parts labeled with numbers. At the top, the text 'Fig. 6' is written in a stylized font. Below it, the number '48' is written vertically. The frame has several holes and a central slot. Various parts are labeled with numbers: '39' is on the left side of the frame; '138' is on the right side; '40' is on the far right; '43' is at the bottom left; '42' is at the bottom right; '20' is at the bottom left; and '37' is at the bottom right. The drawing uses hatching and cross-hatching to indicate different materials or sections of the assembly.

UNITED STATES PATENT OFFICE.

FOREST E. MILLER, OF NEWBERRY, SOUTH CAROLINA.

GRITS-SEPARATOR.

1,226,562.

Specification of Letters Patent. Patented May 15, 1917.

Application filed December 14, 1915. Serial No. 66,795.

To all whom it may concern:

Be it known that I, FOREST E. MILLER, a citizen of the United States, residing at Newberry, in the county of Newberry and State of South Carolina, have invented new and useful Improvements in Grits-Separators, of which the following is a specification.

This invention relates to grits separators for separating grits from bran and meal, and it has for its object to produce a machine of simple and improved construction, whereby at a single operation two grades of grits, coarse and fine, may be separated from the bran and the meal, thus securing four products by a single passage of material through the machine.

A further object of the invention is to produce a machine of the class described of simple and improved construction, by the use of which the several grades of grits will be subjected to independent blasts of air from a single fan for the purpose of eliminating impurities.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings,—

Figure 1 is a side elevation of a machine constructed in accordance with the invention.

Fig. 2 is a top plan view of the same.

Fig. 3 is a longitudinal sectional view taken on the line 3—3 in Fig. 2.

Fig. 4 is a transverse sectional view taken on the line 4—4 in Fig. 1.

Fig. 5 is a transverse sectional view taken on the line 5—5 in Fig. 3.

Fig. 6 is a transverse sectional view taken on the line 6—6 in Fig. 3.

Figs. 7 and 8 are detail views of portions of the coarse and fine grits sieves and related parts.

Corresponding parts in the several figures are denoted by like characters of reference.

The frame 15 of the improved machine which is provided with legs or corner posts 16 supports a hopper 17 and a fan casing 18, 60 the latter containing the rotary fan 19 which is mounted on a shaft 20. The hopper contains a corrugated feed roller 21 mounted on a shaft 22, said corrugated roller operating in conjunction with the feed gate 23 to regulate the passage of material from the hopper to the shoe 24. The latter consists of a suitable casing which is supported for reciprocation, and it is actuated by means of a lever 25, one end of which is connected 65 by a pitman 26 with a crank 27 on a main driven shaft 28, the latter having a pulley 29 whereby it is driven from a suitable source of power, it being obvious that, if desired, the shaft may be manually rotated. 70 The driven shaft 28 has a pulley 30 from which a belt or band 31 is trained over pulleys 32, 33 on the shafts 20 and 22, respectively, thereby transmitting motion to the fan and to the feed roller, it being evident 75 that pulleys of proper dimensions will be used to secure the desired relative speed of the parts. For the purpose of securing the feed gate 23 in adjusted position any convenient means, such as a bolt 23' carried by 80 a bracket 24' and engaging a slot 25' in the feed gate may be employed.

The shoe 24 contains a bran sieve 34, a coarse grits sieve 35 and a fine grits sieve 36, arranged in the order named, the bran sieve being uppermost. The shoe has an outlet for the meal sifting through the fine grits sieve, said outlet consisting of a spout 37 which is slidably connected with the shoe from which it extends laterally through an opening in the side of the casing, a flanged guide member 37' being provided to support the said spout. The latter, as seen in Fig. 5, is provided with a hook portion 38' adapted to engage a pin 39' lying in the path thereof to limit the outward movement of the spout. By pushing the spout inward within the shoe the latter may be raised clear of the frame or outer casing whenever needed in order to afford access to underlying parts.

Extending forwardly from the fan casing and communicating with the outlet of said casing is a wind trunk 38 having a longitudinal partition 39, whereby separate com-

partments 40 and 41 are formed, each of said compartments being provided with an outlet designated, respectively, by 42 and 43. The bran sieve 34 projects beyond the 5 tail end or discharge end of the shoe 24, and it overhangs the tail end of the wind trunk so that bran discharged over the sieve 34 will be blown clear of the machine. The sieves 35 and 36 are provided, respectively, 10 with deflectors 44 and 45, whereby material discharged over said sieves will be conveyed to hoppers or funnels 46, 47 communicating, respectively, with the compartments 40, 41 of the wind trunk, said hoppers being positioned directly above the outlets 15 42, 43. The material discharged over the sieves 35, 36 will thus be subjected to the blast of the fan before reaching the outlets 42, 43, and the coarse and fine grits will thus 20 be cleaned from dust, fine bran and other impurities, the impurities mingling with the bran as the latter is blown from the machine. The funnels 46, 47 are each provided with a deflecting lip 48 depending partly within 25 the wind trunk, as clearly seen in Figs. 3 and 6, and over which the grits will be partly guided before subjected to the action of the blast.

It will be seen that by the improved machine, by a single operation, crushed corn 30 may be divided into four distinct commercial products, namely, coarse grits, fine grits, meal and bran, the grits being thoroughly cleansed from all impurities. The machine 35 is simple in construction, economical in operation and thoroughly efficient for the purposes for which it is provided.

Having thus described the invention, what is claimed as new, is:—

40 1. In a grits separator, a trunk having a longitudinal vertical partition whereby compartments are formed lying adjacent to each other with their bottom portions in the same plane, each compartment having an inlet in its top portion and an outlet in its bottom portion, the outlets being in vertical registry with the inlets and each inlet having a funnel, a shaking shoe having a bran sieve overhanging the wind trunk to discharge 45 material in the path of the air current issuing 50

ing therefrom, and sieves in the shaking shoe having deflectors to discharge material from the separate sieves to separate inlet funnels.

2. In a grits separator, a trunk having a 55 longitudinal vertical partition whereby compartments are formed lying adjacent to each other with their bottom portions in the same plane, each compartment having an inlet in its top portion and an outlet in its bottom 60 portion, the outlets being in vertical registry with the inlets and each inlet having a funnel, a shaking shoe having a bran sieve overhanging the wind trunk to discharge material in the path of the air current issuing 65 therefrom, and sieves in the shaking shoe having deflectors to discharge material from the separate sieves to separate inlet funnels, said shaking shoe being provided with a meal outlet in the bottom intermediate the 70 ends thereof.

3. In a grits separator, a wind trunk having a longitudinal vertical partition producing separate compartments, a shaking shoe having a bran sieve overhanging the 75 discharge end of the wind trunk, sieves in the shaking shoe for the production of products of several grades, and means for conducting said products through the wind trunk in the path of the wind currents issuing 80 through the compartments thereof.

4. In a device of the class described, a wind trunk having a longitudinal vertical partition producing separate compartments, a shaking shoe having a bran sieve overhanging the discharge end of the trunk, sieves in the shaking shoe for the production 85 of several grades, hoppers for conducting said products through the wind trunk in the path of the air currents issuing 90 through the compartments thereof, and lips extending from said hoppers within the compartment of the wind trunk.

In testimony whereof I affix my signature in presence of two witnesses.

FOREST E. MILLER.
